ABSTRACT OF THE DISCLOSURE

An air inlet assembly for an air-conditioning unit which provides a damper arrangement to control both the quantity of air returned to the air conditioning unit from the space served by the unit and the quantity of fresh air supplied to the unit, and mix the two streams of air upstream of air-conditioning elements which can also be provided in the unit.

BACKGROUND OF THE INVENTION

Previous air-conditioning apparatus to heat and/or cool air for a space to be served by the unit, for example, multizone air handling units which can include air heating and air cooling means to provide selectively conditioned air to different locations within a building, have generally provided means for mixing fresh air with a selected quantity of air returned from the space served by the unit. Various air inlet arrangements have been provided in such air conditioners to selectively regulate the quantity of air introduced to the air-conditioning apparatus, but such arrangements have generally not provided means for efficient mixing of the return air and fresh air before redistribution to the spaces served by the unit.

Furthermore, previous air inlet arrangements have required several expensive motor-operated dampers to regulate the flow of fresh and return air to the air-conditioning unit and exhaust a portion of the return air from the unit. The air inlet dampers in such apparatus have been disposed in side-by-side relationship to direct the return air stream and fresh air stream in parallel flow paths. In some such apparatus additional mixing dampers or baffles are provided downstream of the inlet dampers to mix the air streams prior to delivery to the air conditioning elements and in those air conditioners where mixing dampers or baffles are not provided the streams of air are not mixed so some zones served by the unit receive primarily return air while other zones receive primarily fresh air and very few zones receive the desired combination of both.

SUMMARY OF THE INVENTION

The present invention recognizes that it is desirable to provide an air inlet chamber to thoroughly mix controlled portions of air returned from the served space with controlled portions of fresh air drawn into the unit before the air passes through the air-conditioning elements.

The present invention provides a straightforward air inlet arrangement for an air-conditioning apparatus which can include only two motor operated dampers and advantageously provides means for efficient mixing of return air and fresh air streams prior to the introduction of combined streams to the air-conditioning elements of the unit. Therefore, each area served by the air-conditioning apparatus is provided with a more uniform mixture of fresh air and return air.

The present invention further recognizes that by advantageously disposing the dampers controlling the fresh air supply and return air supply within the air inlet

2

chamber in partially facing relation, the two air streams are efficiently mixed and large dampers can be used to reduce the pressure drop experienced by the air stream passing through the dampers so the capacity of the air moving equipment associated with the air-conditioning unit is increased.

Various other features of the present invention will become obvious to those skilled in the art upon reading the disclosure set forth hereinafter.

More particularly, the present invention provides an air inlet assembly to supply a stream of air to an air-conditioning apparatus comprising: a housing having a return air inlet communicating with the space served by the air-conditioning apparatus, a fresh air inlet communicating with a source of fresh air, and an exhaust air outlet communicating with the return air inlet; means to supply air from the space served by the unit to the return air inlet and to supply fresh air to the fresh air inlet; first wall means, including first adjustable air damper means, disposed within the housing to define a return air inlet chamber within the housing communicating with the return air inlet and the exhaust air outlet; second wall means, including second adjustable damper means, disposed within the housing to define a fresh air inlet chamber communicating with the fresh air inlet wherein the second damper means is in partially facing relation with the first damper means so air emitted from the second damper means is directed into the stream of air emitted from the first damper means; damper operator means to selectively modulate the first and second adjustable damper means to regulate the quantity of return air and quantity of fresh air flowing through each of the dampers; exhaust fan means disposed to blow exhaust air through the exhaust air outlet; and, control means to operate the exhaust air fan in response to the position of the adjustable first and second damper means.

It is to be understood that the description of the example of the present invention given hereinafter is not by way of limitation and that various changes can be made in the arrangement, form, and configuration of the apparatus disclosed without departing from the scope or spirit of the present invention.

Referring now to the drawings:

FIGURE 1 is a perspective view, in section, of one example of an apparatus in accordance with the present invention;

FIGURE 2 is an elevational view, partly in section, of the apparatus shown in FIGURE 1; and,

FIGURE 3 is a view taken along a plane passing through line 3—3 of FIGURE 2.

The example of one air-conditioning device in accordance with the present invention as shown in FIGURE 1 includes a housing 1 having an air inlet section comprising a fresh air inlet 3, return air inlet 5, an exhaust air outlet 2, and first air flow control damper 4, and second air flow control damper 6 disposed within housing 1 as hereinafter described. Downstream of the air inlet assembly air treating elements can be provided in the housing and can include, for example, an air filter 16, air blowers 21, an air heating element 32, and air cooling element 33.

Housing 1 can include a framework 1b adapted to receive panels 1a and rest on base frame constructed of channel members 1c as shown. An access door 1d can be provided to permit inspection and service of the unit and facilitate changing the air filter media as hereinafter described. The unit is, advantageously, mounted in contiguous relation with the space to be served, for example, on the roof of a building with the return air inlet 5 in communicative relation with a return air manifold (not shown) from the spaces served by the unit.

In accordance with one feature of the present invention, as shown in the figures, first and second air con-

trol dampers 4 and 6 are disposed within the housing in partially facing relation so the stream of air emitted from return air damper 6 and fresh air damper 4 are mixed. Damper 6 is disposed between wall members 13 and 13a which are connected to one end of the damper 6 and the wall of housing 1, respectively, to define a return air inlet chamber communicating with return air inlet 5 and exhaust air outlet 2 which is provided in housing 1. Return air inlet 5 communicates with a return air manifold to return air from the space served by the unit. Damper 4 is disposed within the housing and walls 12 and 12a, respectively, are provided to have one end to be connected to each end of damper 4 and to the wall of housing 1, as shown, to define a fresh air inlet chamber communicating with the fresh air inlet 3. A louver 3a, FIGURE 2, can be provided to cover fresh air inlet 3 to prevent admission of undesirable materials into housing 1.

Air flow through each damper assembly is controlled by the position of the individual damper blades 4a and 6a of the dampers. The construction of both dampers 4 and 6 is similar in that blades 4a and 6a of both dampers pivot about shafts 7 to crank arms 8. Each arm 8 is pivotably connected to an operator rod 9 so that the respective damper is opened and closed in response to movement of operator rod 9. A motor operator 11 is provided to selectively adjust the air flow opening through each of the dampers and a linking rod 9a (FIGURE 2) is provided to connect motor operator 11 to each damper rod 9, as shown. The damper motor operator is actuated in response to changes in temperature of the stream of mixed air admitted to downstream air conditioning elements 32, 33 to maintain a uniform selected temperature in the air stream. The air temperature can be sensed by a thermal bulb 28 within housing 1, for example, downstream of filter 16 as shown, and the temperature is transmitted to the damper motor operator by means of a conduit 29 and damper motor 11 operates accordingly.

A fan 15 is provided adjacent the exhaust air outlet to exhaust return air from the air-conditioning unit and fan 15 can be adapted to be driven by a motor 15a as shown. It will be noted that a drop damper 10 is provided to cover exhaust air outlet 2 and is opened in response to flow of air through the exhaust air outlet 2, for example when fan 15 is operating. Damper 10 is closed when there is no air flow through outlet 2 and most of the return air received by the unit is recirculated through the unit.

Downstream of the air inlet assembly, and before heating element 32 and cooling element 33, an air filter 16 is provided to remove particulate matter from the air stream passing through the unit. The filter, as shown, can be of the roll type and can include a filter media supply roll 14 and a filter media take-up roll 17 to provide a continuous sheet 16 of filter media, for example spun glass, transversely across the air flow path so that the entire air stream passes through the media. Support means including a frame 19 having intermediate supports 18 can be provided to maintain the media in air filtering relation within the air-conditioning unit. Media supply roll 14 and media take-up roll 17 can be journaled in bearing means 14a and 17a, respectively, and media can be advanced from roll 14 to roll 17 by turning take-up roll 17, for example by crank means (not shown), to draw new media from the supply roll into the air filtering zone. Idle rollers 20 can be provided at opposite edges of frame 19 to lend further support media 16 in air filtering relation. When roll 14 of fresh media is exhausted, take-up roll 17 can be removed through the opening provided by removable panel 1d and new roll 14 of media can be inserted through the opening to be received by journals 14a. The media is then threaded from roll 14 to roll 17. If desired, indicator means (not shown) can be provided to signal the condition of the filter media and to give notifi-

cation when the media has become clogged so clean media can be advanced into the air flow stream.

As shown in FIGURE 1, air blowers 21 can be provided within the unit to provide a stream of air through the air-conditioning unit. In the example of the figures, blowers 21 and a drive motor 23 are carried by a chassis 22 as a compact unit. Chassis 22 can be spring mounted to the air conditioner frame member for example by springs 26, to isolate housing 1 from vibrations associated with operation of the blower assembly. The arrangement, as shown, provides a single drive shaft 24 so that only one motor is required to operate blowers 21. It will be further noted that blowers 21 are located in housing 1 to provide induced draft through the air inlet and the air filtering sections, and forced draft through the air heating and cooling elements downstream of the blowers. The outlets from blowers 21 communicate with an opening in wall 27 and are sealed (by seals 31) along the edges to wall member 27, which extends transversely across the housing so all the air emitted from the blower passes through the opening in wall 27 to the downstream air heating and air cooling elements 32 and 33.

Air heating element 32 and air cooling element 33 are disposed in over and under relationship within the housing as shown in the figures. A horizontal panel member 35 extends from the lower side of air heating elements 32 to the upper side of air cooling element 33, as shown, to define lower and upper air flow paths 34, 38, respectively. A horizontal panel member 37 extends downstream from the cooling element 33 and is joined to an outlet damper assembly in sealing relationship to prevent air flow from the upper flow path to the lower flow path, and vice versa, downstream of cooling element 33. While a heating element 32 as shown in the figures is a direct fired heater, it will be recognized that other type heating elements, for example hot water heat exchangers, can be provided. The cooling element 33 shown in the example of the figures represents a refrigerant evaporator having a condensed refrigerant inlet 39 and an evaporated refrigerant outlet 41 which are connected to a refrigerant compressing and condensing arrangement (not shown).

The outlet damper assembly, as shown, includes co-operative upper and lower dampers 41-41a communicating with separate outlet chambers 42 defined between panels 44. The upper and lower dampers 41-41a are provided to selectively control flow of tempered air to the downstream chambers 42 and the air from each chamber 42 is supplied through duct means (not shown) to a different space served by the air-conditioning unit. A damper motor 45 is provided for each outlet damper 41-41a and can be operated by a remote control thermostat located in a space to be served by the air conditioner. The thermostats operate damper motors 45 to selectively modulate dampers 41-41a to admit proportioned flow of heated air from chamber 38 and cooled air from chamber 34 to provide a selected blend of tempered air in each chamber 42 to be supplied to the served space.

In general, motor operator 11 modulates inlet dampers 4 and 6 to provide a stream of air to heating element 32 and cooling element 33 at a selected temperature. In situations when the outside temperature is in the range of the desired temperature in the served space so some spaces require cooling and others require heating both heating element 32 and cooling element 33 can be operated and the temperature of the air supplied to the space served by the unit is controlled by the position of dampers 41-41a which determine the temperature of the air admitted to chambers 42.

In other cases, depending on the inlet air temperature and the temperature desired in the served space, only air cooling element 33 or air heating element 32 can be operated so a part of the air stream passes over one of the elements 32 or 33 and the air stream passing through the other flow channel is not tempered. The tempered air is

then mixed with untempered air to provide the desired temperature in each chamber 42. Automatic cut-off switches (not shown) can be provided to control the operation of heating element 32 and cooling element 33 in accordance with selected changes in outside air temperature and heating load. Also, in certain operating ranges where the outside air temperature is only slightly below the desired room temperature both air heating element 32 and air cooling element 33 can be turned off so the entire cooling effect required in the space served by the air-conditioning unit can be supplied by uncooled outside air and any heating effect can be supplied by mixing the outside air with a controlled quantity of return air so temperature regulation is controlled entirely by the inlet dampers and controller 11.

Also, it will be recognized that if desired the air inlet damper assembly can be controlled by damper motor operator 11 to provide a minimum flow of fresh air at all times, regardless of whether the air flowing through the unit is heated or cooled.

The invention claimed is:

1. An air inlet assembly to supply air to an air conditioning apparatus comprising: a generally rectangular housing defined by a top wall, bottom wall, spaced first and second side walls and an end wall having a return air inlet communicating with the space served by the air conditioning apparatus, a fresh air inlet communicating with a source of fresh air, and an exhaust air outlet communicating with said return air inlet; means to supply air from said space served by said unit to said return air inlet and to supply fresh air to said fresh air inlet; first damper wall means, including first adjustable air damper means, disposed within said housing and connected to said first side wall and said end wall to define a return inlet chamber within said housing communicating with said return air inlet and said exhaust air outlet; second damper wall means, including second adjustable air damper means, disposed within said housing and connected with said second side wall and said end wall to define a fresh air inlet chamber communicating with said fresh air inlet, said first and second damper wall means being disposed in spaced converging relation so said second damper means is in partially facing relation with said first damper means and so air emitted from said second damper means is directed into said stream of air emitted from said first damper means; damper operator means cooperating with the said converging first and second wall means to selectively control said first and second adjustable damper means to regulate the quantity of return air and quantity of fresh air flowing through said first and second damper means; exhaust fan means disposed to receive air from said return air inlet and exhaust a portion of such air through said exhaust air outlet; and control means to selectively operate said exhaust air fan means in response to change in temperature of a selected air stream passing through said housing.

2. The air inlet assembly of claim 1 including: operator means to selectively control said first and second adjustable damper means to regulate the quantity of return air and quantity of fresh air flowing through said first and second dampers; exhaust fan means disposed to blow exhaust air through said exhaust air outlet; and, control means to selectively operate said exhaust air fan in re-

sponse to selected temperature of air passing through said housing.

3. The apparatus of claim 1 wherein said means to supply said air from said space served by said unit and said means to supply fresh air to said fresh air inlet including blower means disposed within said housing in a position downstream from said air inlet means; and, air heating and air cooling means disposed within said housing downstream of said air blower means to selectively heat and cool air passing through said housing.

4. The air inlet assembly of claim 1 including exhaust damper means disposed to cover said exhaust air outlet, said damper means to be opened in response to movement of air through said exhaust air outlet and to close when flow of air through said exhaust air outlet ceases.

5. An air inlet assembly to supply a stream of air to an air conditioning apparatus comprising: side wall means defining an elongate rectangular housing having a return air inlet adjacent a first end of said housing and communicating with the space served by the air conditioning apparatus, a fresh air inlet adjacent said first end of said housing communicating with a source of fresh air, and an exhaust air outlet communicating with said return air inlet; blower means disposed within said housing to induce return air flow from said space served by said unit through said return air inlet and to induce fresh air flow through said fresh air inlet; first wall means extending between two adjacent walls of said housing at an oblique angle relative to the longitudinal axis of said housing and connected with said walls to form a return air chamber communicating with said return air inlet and said exhaust air outlet and including first adjustable air damper means to control the flow of return air to said blower means; second wall means including second adjustable damper means extending between two adjacent walls of said housing at an oblique angle relative to both said walls to define a fresh air inlet chamber communicating with said fresh air inlet wherein said first damper means and said second damper means are in partially facing relation so air emitted from said second damper means and said first damper means is mixed; damper operator disposed between said converging first and second wall means to selectively control said first and second adjustable damper means to regulate the quantity of return air and the quantity of fresh air flowing through each of the damper means; exhaust fan means disposed within said exhaust air chamber to emit exhaust air through said exhaust air outlet; and control means to operate said exhaust air fan means in response to selected temperature.
